UNITED STATES PATENT OFFICE.

CHARLES E. GODLEY, OF DETROIT, MICHIGAN, ASSIGNOR TO EDMUNDS & JONES CORPORATION, OF DETROIT, MICHIGAN, A CORPORATION OF NEW YORK.

PANELED REFLECTOR.

Original application filed May 8, 1922, Serial No. 559,204. Divided and this application filed May 3, 1924. Serial No. 710,769.

This invention relates to the construction of the reflectors of projecting lamps, especially the headlamps of motor vehicles, and its object is to so divide the reflector 5 into sections that the rays of the light will be projected upon a clearly defined limited area, and in part concentrated upon a restricted portion of such area.

Lamp builders have long sought to provide headlights for vehicles which would give an even illumination of the roadway from immediately in front of the vehicle to a point in advance thereof sufficiently distant to permit the driver to see and avoid 15 all obstructions, and furthermore, to attain this object with the least expenditure of electric current.

Lamps equipped with the well known parabolic reflectors cannot produce this effect as the illumination of the roadway at a given distance from the vehicle is either very restricted or is much fainter than the roadway nearer the vehicle. When such lamps are so positioned that the concentrated light properly illuminates the roadway sufficiently far in advance to permit the driver to avoid obstructions, the roadway nearer the vehicle is left dark. Or if the light bulb is so positioned that the projected rays illuminate the roadway near the vehicle, too much light is projected upward and sidewise where it is liable to blind 25 drivers of other vehicles and pedestrians.

My present invention aims to overcome these objections while still employing a simple reflector of a substantially parabolic type, by deforming the reflector so that different portions thereof will project beams whose cross-sections are similar in shape 30 but different in size, so that the larger beam will afford a general road illumination of considerable spread while the more concentrated beam will afford a driving beam which will light a narrower stretch of road 35 for considerable distance ahead of the vehicle.

Furthermore, my invention consists in deforming a substantially parabolic reflector so that it will project beams of greater 40 width than height. It also consists in providing a reflector of this character which can be manufactured at approximately the same cost as an ordinary paraboloidal reflector and in which the special deformations

will not interfere with the usual machine 55 polishing of the reflecting surface. Moreover, it consists in providing a reflector construction which will be equally suitable for considerable variations both in the spread of the beams and in their relative intensity, 60 and also adapted to be used for substantially all purposes where it is desirable to project beams of relatively different transverse diameters.

In accomplishing these purposes, I employ a reflector of a generally paraboloidal form and subdivide this reflector into a plurality of panels which extend transversely of the directions in which the beam is to be expanded, each of these panels having its 70 longitudinal medial portion disposed forwardly of the general paraboloidal form of the reflector farther than its lateral edges. I vary the depth of the convexity of the cross-section or the width of the panels according to the desired spread of the projected beam, and vary the relation of the central lines of the panels to the vertical plane passing through the axis of the reflector according to the directions in which 75 the beam is to be expanded.

The cross-section of each panel on a line radial to the inner edge of said panel is the same as a horizontal cross-section of the same width of a determining parabola, the 85 center of this cross-section of the determining parabola being in a line passing through the focal center of both bodies and through substantially the middle of said cross-section of said panel, but reversed. 90 This rule holds with reflectors having panels, all of whose sides are parallel and vertical and with reflectors divided into panels of irregular form so long as the cross-sections of these panels are tilted into the 95 planes in which the light is to be spread. For example, if the central lines of the panels in a headlight reflector having a horizontal axis were all in vertical planes, the beams of the reflector would be expanded 100 from circular to elliptical cross-sections with the major axis of the ellipses horizontal. If the ends of such generally upright panels curve slightly toward or away from a vertical plane, the beam will be changed 105 in cross-section substantially to that of a horizontal rectangle.

While such alterations in beam sections

can be accomplished by means of panels of varying transverse sections, I prefer to convex each panel forwardly in the relative transverse sections of a parabola of slightly longer focus than the normal parabolic reflector for the greater distribution, and transverse sections of a parabola of a much longer focus for the more concentrated light. By using the longer-focus transverse sections, the panels can all be of the same width or any predetermined width, the spread of light being determined by the focal length of the parabola used in determining the transverse sections of the panels.

15 By using transverse parabolic sections in the panels I find that the light rays reflected from each panel diverge equally from the axis of the reflector, the rays from each panel covering substantially the anticipated 20 field of light of the different sections.

I have also found that if the convexity of each panel is just the reverse of the normal parabolic section for the same portion of the reflector, using narrower panels for 25 greater concentration and wider panels for the more diffused light, that the width of panels are determined by the width of spread desired in the projected fields.

This application is a division of my co-pending application, Ser. No. 559,204, filed 30 May 8, 1922, which has been restricted to reflectors in which all the panels extend in the general direction of one plane and which may also have their ends bowed relative to 35 said plane if desired.

In the accompanying drawings, Figure 1 is a front elevation of a reflector embodying the present invention. Figure 2 is a section on the line 2—2 of Figure 1. Figures 1^a, 40 2^a, 1^b and 2^b are diagrams showing the method for determining the proper cross-sections of the paraboloidal panels. Figure 3 a front elevation of a slight modified type 45 of reflector and Figure 4 is a section in the line 4—4 thereof.

Similar reference characters refer to like parts throughout the several views.

The reflector 1 is generally parabolic in form. If a light bulb could be made with a 50 filament with substantially no dimensions and this filament mounted at the focus of the reflector, then this reflector, if a perfect parabola, would project a beam of light of the diameter of the reflector. The filaments of light bulbs are, however, of considerable 55 size so that the light projected is in the form of a cone whose surface is somewhat indefinite.

After the parabola has been formed and 60 polished, it is placed between proper dies and its surface is deformed so as to be divided into panels 3 and 4, those next to central aperture 2 of the reflector in Figures 1 and 2 being narrower than those farther 65 away. Each of these panels has substan-

tially straight sides, that is, the contacting sides of two adjacent panels are in a plane parallel to the focal axis of the reflector, and the planes between the panels converge toward each other from one side of the reflector through the reflector to the other side thereof, the surface of each panel being distorted from the original paraboloidal surface or the surface of revolution of a parabola. The result is that added diffused 70 light is projected toward the corners of the main projected field so that instead of a circular field of light, this reflector projects 75 a field which is substantially rectangular.

The desired width of the panels being 80 fixed, the exact cross-sections of the panels may be determined after the manner shown in Figs. 1^a to 2^b inclusive. For any given portion of the panel E shown in Fig. 2^a, I first determine the center G of the cross-section of the corresponding part of the original or true paraboloidal surface 1, as shown in Fig. 1^a. I then draw a line from this point G to the focus F of the true parabolic surface portion and also plot the corresponding portion of a determining parabola P. The focal length of the reflector 1 is indicated by the line B and that of the parabola P by the line C. The point H at which the focal line F G intersects the determining parabola P indicates the central point of a small section of the parabola P' which has the proper curvature for the desired panel cross-section. If this determining parabola is of greater focal length 90 than the parabola 1 (which is part of the true paraboloidal surface from which the reflector is to be formed and which it will still approach rather closely when finished) this curvature is reversed as shown in Figs. 95 1^a and 1^b.

Cross-sections of the panel 3 at other 100 points are similarly determined, each being taken radially to the inner edge of the panel as shown by the lines K in Fig. 2^a. This insures a panel which effects an unusually 105 uniform distribution of light. Owing to the resulting uniform density of the projected beam and of the beam-widening effect due to the edgewise curving of the panels, they cooperate in projecting a beam of 110 approximately rectangular cross-section with its upper and lower borders substantially parallel to the plane of the line E in Fig. 2^a. The lines K indicate how the 115 rays of light are deflected up and down so as to proceed along lines substantially at right angles to the border lines of the panels 120 at the points of reflection.

Where the panels are at any other angle 125 to the vertical plane of the reflector or parallel thereto, the same process for determining the curvature of the panels composing the reflector may be followed, as indicated in Figs. 1^b and 2^b. This is true no 130

matter at what angle the line E, (Fig. 2^b) crosses the side edges of the panels.

Each of the panels presents a transversely convex surface toward the plane of the open 5 end of the reflector and the curvature of such panel at every point in its length is desirably the same as a horizontal cross-section of the determining reflector taken in a line passing through the focal points of 10 both reflectors, reversed and placed so as to coincide with the normal paraboloidal reflector surface at the edges of each panel and tilted into the planes in which the light is to be spread. The curvature of each panel 15 is therefore greatest at the horizontal diameter of the reflector.

This parabolic transverse curvature of the several panels enables me to determine the exact field to be illuminated by the rays reflected by each panel; and the rays of the light from each panel are projected so as to fall evenly upon the entire predetermined field of illumination, that is, illuminate evenly the field on both sides of the axis of 25 the reflector. The angle of diffusion therefore of the rays reflected by any particular panel depends upon the focal length of the determining parabola and upon the width of the panel. Where the focal length of the 30 determining parabola is short and the curvature of the panel is greater, the beams from that panel will be diffused over a greater area than where the focal length is greater, but the diffusion is accurately controlled, 35 which is impossible with panels which are circular or elliptical in cross-section.

Referring again to Figures 1 and 2, it will be noticed that each of the panels is of substantially even width throughout its length. 40 The projected field will therefore be approximately rectangular, that is, the upper and lower edges will be nearly horizontal. The central portion of this field will be more intensely illuminated than the outer 45 portion and this area of intense illumination may be swung up or down as desired by tilting that portion of the reflector which embodies the central panels relative to the two outer groups of panels. That portion 50 of the reflector which is formed into panels whose width is greater in proportion to their depth approaches more nearly a true parabola, and the light projected thereby is therefore more concentrated, that is, projected onto a more restricted field, and I prefer that these panels shall be tilted upward about one degree so that this smaller and more intense field of illumination will be positioned at the upper portion of the less 60 intense but larger field.

Where an automobile headlight is less than four feet from the roadway and the rays therefrom strike the roadway about two hundred feet from the vehicle, the 65 width of the area of intense illumination

should be that of the roadway and it may extend about one hundred feet toward the vehicle. The area of less illumination derived from the more convex panels will extend over this same distance, and in addition thereto extend over space on each side of the intense field and between it and the vehicle. 70

The reflector 6 illustrated in Figures 3 and 4 is formed with panels 7 and 8 which taper upwardly. The transverse curvature of these panels are again determined as above described and the focal axis of the central panels is tilted downward relative to the axis of the outer groups so that an intense field of light will be imposed on a milder field and on the upper portion thereof. The field of light projected by this reflector against a wall at substantially right angles to the axis of the groups of panels 80 85 will have its corners well filled out.

The field of light projected by this reflector will again be approximately rectangular with a brighter central portion and with the corners well filled out. The brighter central portion can be moved up or down by tilting the focal axis of the central portion of the reflector relative to that of the two outer portions and the relative intensities of these two portions of the field will depend 90 on the areas of the panels in the several groups. 95

I claim:—

1. A concave reflector symmetrical with respect to a vertical plane passing through the axis of the reflector and including a number of panels whose bounding edges are in a surface of revolution of a conic section, the medial lines of the panels being in planes which are parallel to the axis of the reflector but incline toward said vertical plane on one side of said axis, each panel departing from said surface of revolution to produce a reflecting surface which will deflect rays of light relative to a horizontal plane. 100 105 110

2. A concave reflector symmetrical with respect to a vertical plane passed through the axis of the reflector, and including a number of tapering surfaces, the bounding edges of said surfaces being in planes parallel to the axis of the reflector which converge from the widest portion of each surface, each surface departing from a general surface of revolution to produce a reflecting surface which will deflect rays of light an amount approximately equal to the angle between the inner of the bounding planes and said vertical plane. 115 120

3. A concave reflector symmetrical with respect to a vertical plane passed through the axis of the reflector, and including a number of tapering surfaces, the bounding edges of said surfaces being in planes parallel to the axis of the reflector which con- 125 130

verge, each surface departing from a surface of revolution to produce a reflecting surface which will deflect rays of light an amount approximately equal to the angle enclosed by the bounding planes, said wedge shaped surfaces all being convex toward the general focus of the reflector.

4. A concave reflector symmetrical with respect to a vertical plane passed through the axis of the reflector, and including a number of tapering surfaces, the bounding edges of said surfaces being in planes parallel to the axis of the reflector which converge, each surface departing from a surface of revolution to produce a reflecting surface which will deflect rays of light an amount approximately equal to the angle between the inner of the bounding planes and said vertical plane, said wedge shaped surfaces all being convex toward the gen-

eral focus of the reflector, the transverse curvature of each portion of each such surface being the same as that of the general curve of a parabola at that point but in the opposite direction.

5. A concave reflector symmetrical with respect to a vertical plane passing through the axis of the reflector and including a number of panels, one of the bounding edges of each of the panels being in a plane which is inclined to said vertical plane, each panel being convex toward the open end of the reflector to diffuse light along horizontal lines and to deflect the rays of light relative to the vertical plane of the reflector, the transverse curvature of each portion of each such surface being the same as that of the general curve of a parabola at that point but in the opposite direction.

CHARLES E. GODLEY.
